Primary Examiner—Cathron Brooks(74) Attorney, Agent, or Firm—Venable; George H. Spencer(57) CLAIM

The ornamental design for a bag, as shown and described.

DESCRIPTION

FIG. 1 is a perspective view of a bag showing my new design; and,

FIG. 2 is an enlarged side elevational view of the bag, the diametrically opposite side of the bag being identical.

1 Claim, 2 Drawing SheetsFIG. 1
